UNITED STATES PATENT OFFICE.

ALBERT W. FLIGOR AND WILL F. TRICE, OF PARAGOULD, ARKANSAS.

DESIGN FOR A REFRIGERATOR.

SPECIFICATION forming part of Design No. 28,200, dated January 18, 1898.

Application filed September 3, 1897. Serial No. 650,537. Term of patent 3½ years.

To all whom it may concern:

Be it known that we, ALBERT W. FLIGOR and WILL F. TRICE, residents of Paragould, in the county of Greene and State of Arkansas, 5 have invented and produced a certain new and useful Design for Refrigerators; and we do hereby declare that the following is a full, clear, and exact description of the invention, which will enable others skilled in the art to

- o which it appertains to make and use the same, reference being had to the accompanying drawings, which form a part of this specification.

Our invention relates to a novel design for 5 refrigerators; and the leading features consist in the hexagonal-shaped receptacle, the circular cover, the circular block secured to the bottom of the receptacle, and the ornamental stud-shaft with which said bottom is o connected.

In the accompanying drawings, Figure 1 is a perspective view of a refrigerator constructed in accordance with our invention. Fig. 2 is an elevation of the same.

In the said drawings the reference-numeral 25 1 designates a hexagonal base provided with a central vertical stud-shaft 2, to which is journaled a cylindrical block 3. To this block is secured the hexagonal bottom 4 of the refrigerator, which latter comprises a hexagonal 30 casing 5, provided with doors 6 and a hexagonal top 7. This top is provided with a circular cover 8.

Having thus fully described our invention, what we claim is—

The design for a refrigerator substantially as herein shown and described.

In testimony that we claim the foregoing as our own we have hereunto affixed our signatures in presence of two witnesses.

ALBERT W. FLIGOR.
WILL F. TRICE.
